(57) **CLAIM**

The ornamental design for an IV spike cover, as shown and described.

DESCRIPTION

FIG. 1 is a front perspective view of an IV spike cover according to the present design;

FIG. 2 is a front view of the IV spike cover of FIG. 1;

FIG. 3 is a side view of the IV spike cover of FIG. 1;

FIG. 4 is a bottom view of the IV spike cover of FIG. 1; and, FIG. 5 is a top view of the IV spike cover of FIG. 1.

The broken lines depicted in FIGS. 1–5 represent unclaimed environmental subject matter and/or unclaimed portions of the IV spike cover and form no part of the claimed design.

1 Claim, 4 Drawing Sheets
